UNITED STATES PATENT OFFICE.

JOHN J. HENNESSEY, OF MILWAUKEE, WISCONSIN.

FRICITION DRAFT-RIGGING FOR RAILROAD-CARS.

SPECIFICATION forming part of Letters Patent No. 733,961, dated July 21, 1903.

Application filed March 20, 1903. Serial No. 148,686. (No model.)

To all whom it may concern:

Be it known that I, JOHN J. HENNESSEY, a citizen of the United States, residing in Milwaukee, in the county of Milwaukee and State of Wisconsin, have invented a new and useful Improvement in Friction Draft-Rigging for Railroad-Cars, of which the following is a specification.

My invention relates to friction draft-rigging for railway-cars.

The object of my invention is to simplify the construction and increase the strength, durability, and efficiency in operation of the friction draft-rigging heretofore patented to me in Letters Patent Nos. 687,826, 700,422, 702,426, 708,850, 716,415, 716,416, 717,676, 717,677, 717,678, and 717,679.

My invention consists, in connection with a draw-bar and draft-iron or extension in line therewith having a straight friction-face on one side and a plurality of double-incline friction-faces on its opposite side, of a single transversely or vertically movable friction-block having a plurality of double-incline friction-faces engaging the double-incline friction-faces on the draft-iron, a transversely-arranged spring acting against said friction-block, and a pair of side plates or stop-castings secured to and between the draft-timbers or center sills of the car and provided with integral horizontally-extending wings or extensions, and a friction plate or surface engaging the straight friction-face of the draft-iron, the friction-block having on its side vertically-extending ribs or guides engaging corresponding ribs or guides on the side plates or stop-castings.

My invention also consists in the novel construction of parts and devices and in the novel combinations of parts and devices herein shown or described.

In the accompanying drawings, Figure 1 is a central vertical longitudinal section, partly in elevation, taken on line 1-1 of Fig. 2. Fig. 2 is a plan view, partly in horizontal section. Fig. 3 is a vertical cross-section on line 3-3 of Fig. 1. Fig. 4 is a detail perspective view of the draft-iron, and Fig. 5 is a detail perspective view of the friction-block.

In the drawings like letters of reference indicate like parts in all of the figures.

In the drawings, A represents the draft-timbers; A', the center sills; A², the cross-sills; A³, the buffer-block; A⁴, the buffer-plate, and A⁵, the carry-iron, and B is the draw-bar of the coupler B', these parts being all of any suitable construction. D is the sliding draw-bar extension or draft-iron, the same being directly in line with the draw-bar and connected thereto by a clip or yoke b, passing through an eye d in the draw-bar extension or draft-iron. The draft-iron D has a straight friction-face d' on one side, preferably its upper side, and a plurality, preferably two, double-incline friction-faces d² d³ on its opposite side, preferably its under side, and stop shoulders or projections d⁴ and d⁵ at its front and rear ends. The draft-iron D is also provided with a central strengthening-web d⁶, extending between or bridging each of the double inclines or pair of inclines d² d³.

F F are a pair of side plates or stop-castings, fitting between the draft-timbers and securely attached thereto by bolts f. Each of the stop-castings F is provided at its central upper portion with an integral horizontal wing or extension F' and with shoulders or sockets f' to receive the ends of the stationary friction-plate G, so as to securely hold and anchor the friction-plate G in position above the longitudinally-movable draft-iron D and in sliding frictional engagement with the straight friction-face d' of the draft-iron and in the central line of draft. The friction-plate G is preferably made in a separate piece from the stop-castings F or their wings F'. The stop-castings F are also provided with upright guides or ribs f², which engage corresponding ribs or guides h on the transversely or vertically movable friction-block H. The horizontally-projecting wings F' of the stop-castings F have upright abutting flanges f³, secured together by rivets f⁴ and interengaging grooves and tongues f⁵ f⁶, which thus rigidly secure the two stop-castings together, and thereby add materially to the strength and rigidity of the draft-rigging as a whole.

The vertically or transversely movable friction-block H is provided with a plurality, preferably two, double-incline friction-faces

$h' h^2 h' h^2$, corresponding to and fitting against the double-incline friction-faces $d^2 d^3$ and $d^2 d^3$ on the draft-iron D. The friction-block H has a central rim or flange h^3 on its opposite 5 or lower side to receive and form a seat for the transversely-acting spring K, which is supported at its lower end in a removable spring-seat or cup K', which is removably secured to the downwardly-extending projections F² of the side plates or stop-castings F by bolts K³ having keys K⁴. The spring-seat or cup K' has flanges K⁵ at its front and rear ends, which embrace the ends of the transversely-movable friction-block H, as will be 10 readily understood from Fig. 1 of the drawings. As the draft-iron D and friction-block H both have a plurality of double-incline friction-faces and as the transversely-acting spring K bears centrally against the friction-block or 15 midway between its ends, although but a single spring is employed, all tendency of the friction-block to tilt or cant, and consequently bind in its guides on the side plates or stop-castings, is effectually prevented or overcome, 20 while at the same time the friction-surfaces are materially increased in area over what 25 they would be if but a single pair of incline friction-faces $d^2 d^3 h' h^2$ were employed, and the durability of the draft-rigging is thus materially increased and its construction simplified.

The side plates or stop-castings F F have shoulders or stops f⁷ for the stop-shoulders d⁵ on the draft-iron to abut against.

35 The side plates or stop-castings F have each, preferably, a series of three upright guides or ribs f² for the friction-block, which engage a corresponding series of upright guides or ribs h on the friction-block. This materially increases the bearing area and face of 40 the transversely-movable friction-block on the side plates or stop-castings and materially adds to the strength and durability of the draft-rigging as a whole, there being four 45 guide shoulders or faces f² on the side plates or stop-castings fitting against four corresponding guide shoulders or faces h on the friction-block H.

I claim—

1. In a friction draft-rigging for railway- 50 cars, the combination with the draw-bar, of a draft-iron in line therewith having a straight friction-face on one side and a plurality of double-incline friction-faces on its opposite side, a transversely-movable friction-block 55 having a plurality of double-incline friction-faces engaging the double-incline friction-faces on the draft-iron, and a transversely-arranged spring bearing against said friction-block, substantially as specified. 50

2. In a friction draft-rigging for railway-cars, the combination with the draw-bar, of a draft-iron in line therewith having a straight friction-face on one side and a plurality of double-incline friction-faces on its opposite 65 side, a transversely-movable friction-block having a plurality of double-incline friction-faces engaging the double-incline friction-faces on the draft-iron, a transversely-arranged spring bearing against said friction-block, a pair of side plates or stop-castings and a stationary friction-plate engaging the straight friction-face of the draft-iron, substantially as specified. 70

3. In a friction draft-rigging for railway- 75 cars, the combination with the draw-bar, of a draft-iron in line therewith having a straight friction-face on one side and a plurality of double-incline friction-faces on its opposite side, a transversely-movable friction-block 80 having a plurality of double-incline friction-faces engaging the double-incline friction-faces on the draft-iron, a transversely-arranged spring bearing against said friction-block, and a pair of side plates or stop-castings 85 furnished with a series of ribs or guides for said friction-block said friction-block having also a series of ribs or guides on each of its sides engaging the corresponding ribs or guides on the side plates or stop-castings, substantially as specified. 90

JOHN J. HENNESSEY.
